ATTORNEY.

UNITED STATES PATENT OFFICE

171,166

APRON

Winifred P. Odom, Cambridge City, Ind.

Application January 23, 1953, Serial No. 23,280

Term of patent 14 years

(Cl. D3—26)

To all whom it may concern:

Be it known that I, Winifred P. Odom, a citizen of the United States, residing at Cambridge City, in the county of Wayne and State of Indiana, have invented a new, original, and ornamental Design for an Apron, of which the following is a specification, reference being had to the accompanying drawing, forming a part hereof.

I claim:

The ornamental design for an apron, substantially as shown.

WINIFRED P. ODOM.
